UNITED STATES PATENT OFFICE.

CHARLES KARPP, OF COLLEGE POINT, NEW YORK, ASSIGNOR OF ONE-HALF
TO H. HERRMANN LUMBER CO., OF NEW YORK, N. Y., A CORPORATION
OF NEW YORK.

ROTARY CUTTER FOR WOODWORKING-MACHINES.

No. 849,794.

Specification of Letters Patent.

Patented April 9, 1907.

Application filed October 9, 1906. Serial No. 338,139.

To all whom it may concern:

Be it known that I, CHARLES KARPP, a citizen of the United States, residing at College Point, in the county of Queens and State of New York, have invented a new and useful 5 Rotary Cutter for Woodworking-Machines, of which the following is a specification.

The invention relates to improvements in rotary cutters for woodworking-machines. 10 The object of the present invention is to improve the construction of rotary cutters for molding and other woodworking machines and to provide a simple and inexpensive one having a plurality of cutters or tools 15 capable of ready adjustment and adapted to be readily renewed when worn out.

A further object of the invention is to provide a rotary cutting device adapted to make a smooth clean cut either against, with, or 20 across the grain and with which the work will require less sandpapering than heretofore.

Another object of the invention is to provide a rotary cutter which will not require 25 much pressure to push the work through the machine.

Furthermore, it is the object of the invention to provide simple and effective means for securing the cutters or tools in their adjustment and for effectually preventing the same from being displaced by the pressure incident to the use of the rotary cutter.

With these and other objects in view the invention consists in the construction and 35 novel combination of parts hereinafter fully described, illustrated in the accompanying drawings, and pointed out in the claims here-to appended, it being understood that various changes in the form, proportion, size, and 40 minor details of construction within the scope of the claims may be resorted to without departing from the spirit or sacrificing any of the advantages of the invention.

In the drawings, Figure 1 is an elevation of 45 a rotary cutter constructed in accordance with this invention. Fig. 2 is a transverse sectional view. Fig. 3 is a detail perspective view of the stock or head. Fig. 4 is a detail perspective view of one of the adjustable cutters or tools. Fig. 5 is a detail sectional view 50 taken on the line 5 5 of Fig. 1, the set-screw being removed.

Like numerals of reference designate corre-

sponding parts in all the figures of the drawings. 5

1 designates a stock or head having a central circular opening 2 to receive a shaft or mandrel and provided with an annular series of projecting peripheral cutter-supporting extensions 3 and intervening clearance-recesses 4, having a slight inward taper. The outer face of each extension is inclined to the radius of the head, and the said extensions 3 are provided in their outer faces with dovetailed grooves 5 to receive dovetail ribs 6 of 65 cutters or tools 7, which may be of any desired number and which may vary in form. The extensions are provided at opposite sides of the grooves or ways with flat bearing-faces which lie beyond the said grooves or ways 70 and which receive similar flat faces located beyond the dovetail ribs at opposite sides thereof. The dovetailed grooves, which extend the entire length of each extension 3, are centrally arranged and are open at each 75 end, and the stock or head is provided at each extension with a transverse perforation 8, enlarged at one end to form an annular recess 9, which intersects the dovetailed groove 5. The perforation 8 is threaded to receive a set-screw 10, which is provided with an enlarged 80 clamping-head 11, adapted to engage the adjacent side edge of the dovetail rib 6 at the point where the recess 9 intersects the groove 5. The head 11 is provided at its outer face 85 with the usual groove to receive the blade of a screw-driver, and the inner face of the head is flat and is arranged in parallelism with the side faces of the stock or head 1. The set-screw 10, which is readily adjustable, is 90 adapted to firmly hold the cutter or tool 7 in its adjustment, and it effectually prevents the cutter or tool from being accidentally displaced by the pressure incident to the use of the rotary cutting device. As the sharp side edge 95 of the dovetail rib is adapted to bite into the inner face of the set-screw, there is no tendency of the set-screw to accidentally unscrew through the rotary motion of the cutting device. 100

The cutters or tools 7 are tangentially arranged, and they are provided with tapering projecting portions having cutting edges 12, formed by beveling the engaging cutting ends, and the beveled end faces 13 of the cutters or tools are arranged in alinement with 105

the adjacent side walls of the clearance-recesses 4. The cutters or tools have steep bevels, and as there is ample clearance-space afforded by the recess the rotary cutting device will make a smooth clean cut when cutting with, against, or across the grain, and the work will require little sandpapering. The rear ends 14 of the cutters or tools have a slight bevel, and the rear end faces are arranged in alinement with the adjacent side walls of the clearance-recesses; but as the cutters or tools become worn they may be advanced to preserve the proper position of their cutting edges. The cutters take the full width of the head, as the dovetailed ribs offset the cutting edge from the head and do not affect the same. The outer faces 15 of the cutters or tools are concavely curved in cross-section, and the cutting edges 12 are curved, as clearly illustrated in Figs. 2 and 4 of the drawings. The concavely curved cutting edges 12 are designed for cutting molding; but a cutter or tool having a straight cutting edge or a cutting edge of any other desired form may be employed, as will be readily understood. As the cutting ends of the tools or cutters are beveled, as shown, the said tools or cutters do not require a skilled mechanic to sharpen them, and when they are worn out they may be renewed without discarding the stock or head 1.

In practice the rotary cutting device will be provided with a suitable gage for enabling the cutters or tools to be accurately adjusted.

35 It will be seen that the rotary cutting device is adapted to make a smooth clean cut and that it is adapted to effect a saving in both time and labor, as it will enable the material to be run through a machine with little pressure, and it will not require the services of a skilled mechanic to sharpen or adjust the cutters or tools.

Having thus fully described my invention, what I claim as new, and desire to secure by 45 Letters Patent, is—

1. A device of the class described comprising a stock or head provided with a plurality of peripheral extensions and having intervening clearance-recesses, said extensions being provided with grooves, a plurality of tangentially-arranged cutters adjustably mounted on the said extensions and extending into the grooves thereof, and set-screws mounted on the stock or head and provided 55 with heads engaging the cutters and securing the same in their adjustment.

2. A device of the class described comprising a stock or head having a plurality of peripheral extensions and intervening recesses, 60 said extensions being grooved and the stock or head being provided with transverse perforations, the latter being enlarged at one end to form recesses which intersect the grooves of the extensions, cutters mounted 65 on the extensions and extending into the

grooves thereof, and set-screws arranged in the said perforations and having heads located in the recesses and engaging the cutters at the points of intersection of the recesses and the grooves.

3. A device of the class described comprising a stock or head provided with spaced peripheral extensions having dovetailed grooves, said stock or head being also provided with transverse perforations enlarged at one end 75 to form recesses, which intersect the dovetailed grooves, cutters having dovetail ribs arranged in the said grooves and exposed at the points of intersection of the grooves and the recesses, and screws mounted in the perforations and having heads located within the recesses and provided with flat inner faces for engaging the dovetail ribs at the side edges thereof.

4. A device of the class described comprising 85 a stock or head provided with an annular series of peripheral extensions having tapered projections and provided with dovetailed grooves or ways and having flat bearing-faces at opposite sides of the grooves or ways at points beyond the same, said stock or head being also provided with inwardly-tapered clearance-recesses, located between the said extensions and having inwardly-converging side walls, and tangentially-arranged cutters provided with dovetail ribs adjustably mounted in the grooves or ways of the extensions, said cutters having flat inner faces at opposite sides of the ribs to fit 90 against the flat faces of the extensions, and having beveled faces at their engaging or cutting ends arranged in the same plane as the contiguous side walls of the clearance-recesses.

5. A device of the class described comprising 105 a stock or head provided with an annular spaced series of peripheral extensions having centrally-disposed dovetailed grooves or ways, which extend throughout the length of each extension and are open at each end, 110 the outer face of each extension being inclined to the radius of the head, said stock or head being also provided with clearance-recesses located between each of the said extensions, and tangentially-arranged adjustable cutters of a width coincident with the width of the stock or head and having cutting edges of corresponding width, said cutters being also provided with central longitudinal dovetail ribs offset from the inner 115 side faces of the cutters and mounted in the ways, and means for securing the cutters in their adjustment.

In testimony that I claim the foregoing as my own I have hereto affixed my signature 125 in the presence of two witnesses.

CHARLES KARPP.
